PREPARATION OF PHOSPHATIDES

Ralph A. Marmor and Wendell W. Moyer, Decatur, Ill., assignors to A. E. Staley Manufacturing Company, Decatur, Ill., a corporation of Delaware

No Drawing. Application June 17, 1947,
Serial No. 755,255

7 Claims. (Cl. 260—403)

1

This invention relates to improvements in the recovery of phosphatides from oleaginous raw materials, and particularly to such recovery wherein glyceride oil and phosphatidic material are simultaneously extracted from oleaginous material with a liquid solvent, followed by bleaching or decolorizing at low temperature before removing the solvent from the extract, or miscella.

A primary object of the invention is to improve the color and odor of crude phosphatides obtained by extraction of oleaginous vegetable material with a liquid that is a solvent for the glyceride oils contained in such vegetable material.

Another object of the invention is to reduce or substantially eliminate the necessity for bleaching the recovered phosphatides heretofore required to make them acceptable for many uses, chiefly in foodstuffs.

Additional objects of the invention will become apparent from the description and claims that follow.

The invention accordingly comprises the several steps and the relation of one or more of such steps with respect to each of the others thereof, which will be exemplified in the process hereinafter disclosed, and the scope of the application of which will be indicated in the claims.

It is well known that many oleaginous vegetable materials contain appreciable proportions of crude phosphatides, sometimes referred to as lecithin. Among such materials are soybeans, cottonseed, corn germs, rape seed, peanuts and linseed. Attempts heretofore have been made to obtain the phosphatides from their source materials by extracting the latter with a liquid solvent in which the phosphatides are preferentially soluble. Such attempts have not proven satisfactory because the solvents used always extracted much oil, coloring matters, and other impurities which had to be separated from the phosphatidic material at considerable expense.

It is also known that the conventional solvent extraction of glyceride oils from oleaginous vegetable materials extracts a large part of the phosphatides present in the raw material with the oil, and that such co-extracted phosphatides can be readily precipitated and separated from the oil by stirring it vigorously with small proportions of water. The ratio of extracted oil to extracted phosphatides is large, usually exceeding 20 to 1. The so-called gum or crude phosphatidic material thus obtained is a hydrosol con-

sisting chiefly of water, oil, and phosphatides. Minor constituents frequently present include fatty acids, proteinaceous materials, sterol derivatives and color bodies. When dried, the gum usually contains from 60 to 65 per cent phosphatides. At present, this is one of the principal commercial methods of manufacturing crude phosphatide.

Although large quantities of crude phosphatide are easily and economically manufactured as described above, such material has found little application as such in many potential uses, especially in foodstuffs, because of its dark color and strong odor. Heretofore, it has been necessary to decolorize, and at least partially to deodorize, the crude phosphatidic material before it could be satisfactorily used for many purposes. Although several conventional methods are available for correcting the color and odor deficiencies of the crude phosphatide, all possess one or more drawbacks with respect to processing time, apparatus required, cost of reagents, and the like.

The objectionable color and odor of crude phosphatide obtained as described above are apparently due to the high temperatures conventionally employed to free the extracted oil of solvent. The bulk of the solvent is evaporated from the extract or miscella at atmospheric pressure and the remainder is removed by distillation under reduced pressure, frequently with the aid of superheated steam. During the latter operation, the oil is commonly heated to temperatures as high as 100° to 120° C. and held there for substantial periods of time. Prior to this, the oil is also held for considerable periods of time at and above the boiling point of the solvent. In the case of hexane, the solvent most widely used at present, the temperature ranges from about 70° to 100° C.

We have discovered that the color and odor of the crude phosphatide obtained by extracting oleaginous vegetable material with a solvent for glyceride oils and treating the extracted oil with water as described above can be greatly improved by treating the miscella with a color adsorbent prior to evaporating the solvent from the oil. These beneficial results are apparently due to removal of color bodies and other impurities from the oil before they become fixed or altered by the heating that accompanies conventional removal of solvent from the miscella. As pointed out above, the upper temperatures attained by the oil in the conventional solvent removing steps range from about 100° to 120° C. It is to be

noted also that these upper temperatures are reached by the oil, during removal of the last portions of solvent, even when such a low boiling solvent as propane is used to extract the oil from its raw material.

Any of the color adsorbents conventionally used for decolorizing glyceride oils are suitable in the practice of our invention. Among these are activated carbon, magnesia, alumina, and clay; and among the bleaching agents may be mentioned hydrogen peroxide, benzoyl peroxide, chlorine dioxide, and sulfur dioxide. The color adsorbents may be activated by any of the methods well known in the art.

The following examples illustrate our invention in more detail:

Example 1

Flaked soybeans are extracted in a conventional manner with so-called hexane to provide an extract or full miscella comprising about one part soybean oil to three parts hexane. Six liters of such miscella were agitated with about 30 grams of an acid activated bleaching clay for about one hour at 25° to 30° C. The clay was filtered from the mixture, and the noticeably decolorized miscella was heated over a steam bath at about 100° C. to remove most of the solvent from the oil. The residual crude oil, still containing considerable solvent, was then heated over the same bath under a reduced pressure of about 20 mm. of mercury to distill out additional solvent. The last portion of solvent was separated from the oil by passing superheated steam at about 120° C. into the hot oil under the same vacuum. The solvent-free oil was then stirred vigorously for several minutes at about 70° C. with about two per cent of water and allowed to stand until the hydrated gum settled out. This required about four hours. Supernatant oil was decanted from settled gum, and the latter, together with adhering oil, was transferred to bottles and centrifuged to provide additional separation of gum from adhering oil. The gum thus obtained was much lighter colored and had a much less objectionable odor than gum obtained in the same way from conventional crude solvent extracted soybean oil.

Example 2

Dried corn germs were substituted for the flaked soybean in Example 1. The gum thus obtained from the crude solvent extracted corn oil was much lighter colored and of a more pleasant odor than gum obtained by water washing conventional crude solvent extracted corn oil.

Example 3

Substitution of linseed for flaked soybeans in Example 1 yielded the same results with respect to color and odor of the crude phosphatides obtained from the crude oil.

Substitution of activated vegetable carbon, alumina, and magnesia separately for the acid activated clay in the foregoing examples provided gums of similar superior color and odor. The activated carbon, alumina, and magnesia were selected from the types commonly used in the refining of glyceride oils.

Example 4

Flaked soybeans were extracted in a conventional manner with hexane to provide an extract or full miscella comprising about one part soybean oil to three parts hexane. Six liters of this

miscella was stirred for three hours at 50° C. with 10 grams of powdered benzoyl peroxide, then filtered to remove any unreacted peroxide. The filtered and noticeably decolorized miscella was heated over a steam bath at about 100° C. to evaporate the bulk of the solvent from the oil. The crude oil thus obtained, still containing some solvent, was then heated over the same bath under a reduced pressure of about 20 mm. of mercury to distill out additional solvent. The remaining solvent was separated from the oil by passing superheated steam into the hot oil under the same vacuum. The substantially solvent-free oil was then stirred vigorously for several minutes at about 70° C. with about 2 per cent of water and allowed to stand until the hydrated phosphatides settled out. This required about four hours. Supernatant oil was then decanted from the settled phosphatides, and the latter, together with adhering oil, were transferred to bottles and centrifuged to separate additional adhering oil from the phosphatides. The phosphatidic material thus obtained was much lighter colored and less odorous than usual.

If desired, the crude solvent extracted glyceride oil, after being decolorized and freed of solvent in accordance with the principles of our invention, may be degummed at either higher or lower temperatures than indicated in the foregoing examples. Also, the gum may be precipitated with aqueous solutions of acids, bases, and salts instead of water alone as employed in the examples. The use of aqueous solutions of bases is not recommended in the practice of this invention, however, because the gum obtained will be contaminated with the corresponding salts of any free fatty acids present in the crude oil. And if the degumming solution is a concentrated solution of caustic alkali, such as used in the alkali refining of glyceride oils, partial saponification of the phosphatides is apt to occur.

Phosphatides manufactured in accordance with this invention have a number of known and potential uses. Among these are reducing the viscosity of chocolate coating materials, preventing the foaming and spattering of heated margarine, facilitating the wetting of powders and textiles.

Any of the solvents conventionally used for the extraction of glyceride oils from oleaginous vegetable materials may be used in the practice of our invention. The currently preferred solvent in commercial use is hexane, a high test gasoline boiling over a range of about 63° to 70° C. Other solvents such as trichloroethylene, benzene, and ethanol, all having boiling points under 90° C., have been used.

Preferably, the temperature at which the extract is treated with a color adsorbent should not exceed about 60° C. Owing, however, to dilution of the oil and color bodies with the solvent, and to the fact that the color bodies are rapidly adsorbed, the temperature may range upwardly with the same latitude as it does in the extraction operation.

It is not essential to successful coagulation of phosphatides from solvent extracted glyceride oils with an aqueous medium that all the solvent be separated from the oil. The maximum proportion of solvent that may remain with the oil and still permit good coagulation of the phosphatides varies with the kind of solvent. In general, however, as much as 15 per cent to 20 per cent of solvent may be tolerated in the oil from which phosphatides are to be prepared in accordance with this invention.

Since certain changes may be made in carrying out the above process without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

We claim:

1. The process of manufacturing phosphatides, which comprises extracting oleaginous vegetable material from a raw material with a solvent selected from the group consisting of hexane, trichloroethylene, benzene and ethanol to provide an extract of glyceride oils, phosphatides, and solvent, subjecting said extract to the action of a decolorizing agent, evaporating solvent from the extract to provide a mutual solution of said glyceride oils and phosphatides, and agitating said solution with an aqueous medium, whereby crude phosphatides are separated from the bulk of the glyceride oils.

2. The process of manufacturing phosphatides, which comprises extracting oleaginous vegetable material from a raw material with hexane to provide an extract of glyceride oils, phosphatides, and hexane, subjecting said extract to the action of a decolorizing agent, evaporating hexane from the extract to provide a mutual solution of said glyceride oils and phosphatides, and agitating said solution with an aqueous medium, whereby crude phosphatides are separated from the bulk of the glyceride oils.

3. The process of manufacturing phosphatides, which comprises extracting oleaginous vegetable material from a raw material with trichloroethylene to provide an extract of glyceride oils, phosphatides, and trichloroethylene, subjecting said extract to the action of a decolorizing agent, evaporating trichloroethylene from the extract to provide a mutual solution of said glyceride oils and phosphatides, and agitating said solution with an aqueous medium, whereby crude phosphatides are separated from the bulk of the glyceride oils.

4. The process of manufacturing phosphatides, which comprises extracting oleaginous vegetable material from a raw material with benzene to provide an extract of glyceride oils, phosphatides, and benzene, subjecting said extract to the ac-

tion of a decolorizing agent, evaporating benzene from the extract to provide a mutual solution of said glyceride oils and phosphatides, and agitating said solution with an aqueous medium, whereby crude phosphatides are separated from the bulk of the glyceride oils.

5. The process of manufacturing phosphatides, which comprises extracting flaked soybeans with a solvent selected from the group consisting of hexane, trichloroethylene, benzene and ethanol to provide an extract of soybean oil, phosphatides, and solvent, subjecting said extract to the action of a decolorizing agent, evaporating solvent from the extract to provide a mutual solution of said soybean oil and phosphatides, and agitating said solution with an aqueous medium, whereby crude phosphatides are separated from the bulk of the soybean oil.

6. The process of manufacturing phosphatides, which comprises extracting linseed with a solvent selected from the group consisting of hexane, trichloroethylene, benzene and ethanol to provide an extract of linseed oil, phosphatides, and solvent, subjecting said extract to the action of a decolorizing agent, evaporating solvent from the extract to provide a mutual solution of said linseed oil and phosphatides, and agitating said solution with an aqueous medium, whereby crude phosphatides are separated from the bulk of the linseed oil.

7. The process of manufacturing phosphatides, which comprises extracting corn germs with a solvent selected from the group consisting of hexane, trichloroethylene, benzene and ethanol to provide an extract of corn germ oil, phosphatides, and solvent, subjecting said extract to the action of a decolorizing agent, evaporating solvent from the extract to provide a mutual solution of said corn germ oil and phosphatides, and agitating said solution with an aqueous medium, whereby crude phosphatides are separated from the bulk of the corn germ oil.
